LINE CASTING MACHINE

Lester M. Walden, New York, N. Y., assignor to
Teletype Corporation, Chicago, Ill., a corpora-
tion of Delaware

Application June 7, 1934, Serial No. 729,348

5 Claims. (Cl. 199—24)

The present invention relates generally to line-casting and composing machines and more particularly to automatic control apparatus that is adapted to be used in conjunction with such machines for controlling the composing and line-casting functions thereof.

This invention in its preferred embodiment has application to commercially standard structures of linecasting and composing machines that are provided with matrix storage magazines each having a plurality of channels adapted to receive certain quantities of character bearing matrices. In accordance with conventional practices, the length of these channels is limited so that but a maximum quantity of matrices may be received within each channel, which ordinarily may be ample for line composition requirements, but when used in conjunction with automatic control devices and particularly in the case of certain frequently used matrices, the quantity of such matrices that may be supported within these channels may be inadequate for supplying a machine in the course of certain line composition.

Among the characters whose occurrence in ordinary text is such as to exceed the supply that may be availed of in the capacity of but a single channel, the most frequently depleted is the letter "e", though in certain classes of line composition, other characters may be equally affected. To compensate for this inadequacy, it has been the practice heretofore to allot pluralities of channels for the purpose of storing those certain characters having frequent occurrence during line composition, while the remaining characters have the conventional accommodation of but a single channel for each class or character of matrix. It has been known heretofore accordingly that where pluralities of channels are employed for housing similar matrices, means may be provided for manually associating matrix release apparatus with each of said pluralities of channels in accordance with a predetermined succession so as to draw from the supply of each channel and to avoid depleting any one of the channels which might produce a failure of response during a subsequent matrix release operation, because no matrices are available in the associated supply channel.

It is accordingly a salient object of the present invention to provide a mechanism that is automatically and periodically responsive to the supervision of an automatic control unit for associating a common matrix release mechanism with each of a plurality of matrix channels.

In carrying out the above and other objects of

the present invention, a preferred embodiment has been illustrated in the accompanying drawing which has been applied to an automatic control unit such as the one more fully illustrated and set forth in copending application Serial No. 5 600,606, filed March 23, 1932 in which there is provided a record reader mechanism which obtains its operating power from the driving source conventionally provided with commercial types of linecasting machines, to be referred to herein- 10 after generally as the principal machines. In accordance with this type of structure, a power take-off mechanism is provided having tributary thereto a pair of driving branches one of which operates to actuate the several elements of the 15 record reader mechanism and its associated mechanical selector and another of which operates periodically to actuate an elevator raising mechanism for delivering assembled lines of matrices from a lower level where the matrices are assem- 20 bled during line composition to an upper level at which they are removed to be carried to a slug casting chamber associated with the principal machine.

A perforated tape previously prepared contains 25 successively transverse rows of perforations each of which corresponds to a character to be composed or to a collateral function which is to be controlled in the performance of the linecasting machine. After a predetermined number of 30 character selecting perforations, one such function perforation follows which is adapted to initiate the performance of the elevator operating mechanism. Coincident with the operation of the elevator, the record reader mechanism is 35 momentarily arrested by the interruption from rotation of its driving branch, during which time, the driving branch associated with the elevator operating mechanism is initiated into performance. After the elevator has completed its 40 delivery operation, the driving branches are restored to their original condition, that is, the record reader operating branch is started into operation and the elevator operating branch becomes inactive.

To regulate the associative control of the two aforementioned driving branches, there is provided an intercontrol device whereby, during the performance of each of the branches, the other is disabled. This intercontrol device describes 50 a short movement coincident with each elevator performance and in controlling the operation of the mechanism more particularly relating to the present invention, this movement of the intercontrol device is utilized. This motion is recip- 55

rocal, and is transmitted through a leverage system by means of a pawl which causes to be rotated a ratchet wheel and shaft associated therewith. A cam carried by said shaft is provided with a plurality of apices or high points and nadirs or low points which present themselves alternately and during successive cycles.

A lever responds to this reciprocal motion through suitable linkage, and is connected with a carriage that supports a plurality of horizontally shiftable release reeds that are capable, during each presentation, of being associated with a corresponding one of a plurality of adjacent matrix channels. In this manner the successive elevator operations being representative of corresponding performances of line composition, are caused to shift the release mechanism of certain characters to be associated with various ones of a plurality of channels.

For a better understanding of the present invention, reference should be had to the accompanying drawing and to the following description wherein like reference characters designate similar parts throughout.

A tape sensing mechanism, generally referred to as a record reader, is indicated by the reference character 11. This device responds to transverse rows of perforations in a tape 12 and accordingly causes to be positioned a set of code bars 13. For each condition of the several code bars, a function performing element is placed into selective condition. Among several such elements one indicated 14 is delegated to the function of initiating the performance of the matrix assembly elevator operating mechanism. Upon being selected, it is moved forward (towards the observer as illustrated in the accompanying figure), and in so doing, rotates a three-armed lever 15 in a counterclockwise direction. To one of the arms of lever 15 is connected a latch bar 16 and to the latter is pivotally articulated at 17 one end of a floating lever 18. The opposite end 19 of lever 18 is supported between a pair of forked elements integrally formed with a connecting rod 21, the opposite end of which is pivoted at 22 to a depending arm of a cradle member 23 which rocks about a horizontally supported shaft 24.

Another arm 25 of cradle member 23 extends downwardly and leftwardly, as viewed in this figure, and is shaped arcuately and provides inwardly thereof a short radius section 26 and a somewhat longer radius section 27. In cooperation with these sections there is supported a camming lever 28, the depending portion 29 of which is provided with a beveled section which engages the surfaces 26 and 27 in accordance with the position of lever 28. A spring 30 tends to maintain the follower roller 31 of lever 28 in constant engagement with a delivery slide arm 32. Following the raising of the assembling elevator when the latter attains the line delivery slide level, slide arm 32, rocking counterclockwise in a well-known manner, together with the movement of the line delivery slide, rotates about its pivot 33, withdrawing its surface from engagement with roller 31 and permitting a spring 34, connected to a cooperating bail 35, to urge lever 28 also in a counterclockwise direction about its pivot 31.

In so doing, the beveled surface 29 is withdrawn from engagement with short radius surface 26 and presented opposite long radius surface 27. This permits cradle member 23 to be rotated clockwise as is its tendency to do un-

der the influence of a spring 36 which urges connecting rod 21 leftwardly.

The utility of floating lever 18 and its cooperation through connecting rod 21 and cradle 23 as an intercontrol device between the record reader mechanism 11 and the delivery slide arm 32 is well known and forms the subject matter of a copending application Serial No. 600,606, filed March 23, 1932 mentioned above. Because of its frequency of operation, it is particularly adapted to initiate the performance of the mechanism constituting the present invention and about to be described. For purposes of understanding the present invention, suffice it to say that the aforescribed reciprocal movement of lever 28 coincides with each elevator operation which in turn corresponds with the assembling and delivery of each group of matrices that is composed for the purpose of casting a line slug.

Integrally formed with cooperating bail 35 is an upstanding arm 36 to which is connected a pawl 39, spring urged to engage the teeth of a ratchet wheel 41, while a latch pawl 40 pivoted to a stationary part of the machine also engages the teeth of wheel 41. In accordance with the particular illustration, ratchet wheel 41 is provided with eight ratchet teeth in longitudinal alignment with eight corresponding positions on a quadrilateral cam 42. In other words, alternate teeth of wheel 41 coincide with associated apices 43 and nadirs 44 of cam 42.

A lever 45, pivoted at 46 is provided with a depending arm 47 having a projecting portion that is urged by a spring 48 to engage the periphery of cam 42. The opposite or upstanding arm of lever 45 is connected as at 49 to a spring 51, which in turn is secured to a lug 52 integrally formed with a horizontally slidable bar 53. As the cam 42 is rotated, it presents alternately an apex 43 and a nadir 44 to the projection of depending portion 47 of lever 45.

This causes lever 45 to reciprocate coincident with each actuation by pawl 39 of wheel 41 and cam 42 and accordingly to impart a similar movement to bar 53, spring 51 acting as a resilient element to prevent possible rupture that might otherwise result if the movement of bar 53 were impaired and it could not respond to the urge of lever 45.

Throughout its length, bar 53 is provided with notches 54 within which reside individual release reeds 55 free to vertical movement that may be imparted thereto through the escapement mechanisms 56 that are tripped by the weight bars 57 under the actuation of levers 58 which may be controlled either manually by means of key tops 59 or automatically through the agency of the bell crank levers 61, as described in the copending application referred to above.

When bar 53 is moved horizontally, it accordingly shifts reeds 55 into either of alternative positions as indicated in solid and broken lines, during which the reeds 55 are each permitted to register with one or the other of a pair of cooperating reeds 62 and 63 with which each shiftable reed 55 is associated. Cooperating reeds 62 and 63 control escapement elements 64 of adjoining matrix channels 65. During the association of a main operating reed 55 with its cooperating reed 62, the selective operation thereof causes to be released matrices from one of the adjacent channels 65, while during the association thereof with the other cooperating reed 63 there may be effected the release of matrices from the adjoining channel 65. Since the shift-

ing lever 45 operates to shift reeds 55 coincident with consecutive elevator operations, matrices from adjoining channel 65 are alternately released in accordance with successive lines of composition. This permits of a larger source of supply to be availed of under the control of a single release reed 55.

When the matrices are released from their respective channels, they are permitted to precipitate through individual chute chambers that are arranged in a collective chute 66, whence they are carried in a well-known manner to the assembling block in the course of line composition.

It should be understood that the association of the shift operating mechanism forming one adaptation of the present invention may be associated with other actuating devices than the one illustrated in the instant case, namely, the elevator operating mechanism. Likewise, it should be understood that numerous changes and modifications may be made without departing from the spirit or scope of the present invention. For this reason it is not intended to be limited to the details illustrated in the accompanying drawing nor to the language employed in the foregoing specification, but to be permitted instead a latitude of interpretation as indicated by the hereinafter appended claims.

What is claimed is:

1. In a linecasting and composing machine, a plurality of matrix release members arranged in horizontal alignment, a release reed, means for shifting said reed so as to present it into registration with diverse ones of said release members including a shifting lever, a matrix delivery slide operating lever, means conditioned upon the movement of said operating lever for imparting motion to said shifting lever, and an automatic control apparatus for initiating the performance of said operating lever.

2. In a linecasting and composing machine, a composing mechanism including escapements, a plurality of release reeds shiftable into alternate escapement actuating positions, an automatically operated device responsive to the code characters in a control form for selectively actuating said release reeds, a lever for controlling the operative connection between a source of power and said device, a line delivery slide arm for moving assembled matrices, and a member actuated by said line delivery slide arm for operating said lever and for shifting said release reeds into alternative positions.

3. In a linecasting and composing machine, a plurality of matrix release escapements, a plurality of matrix release reeds for actuating said escapements, a line delivery slide lever power driven for moving assembled matrices horizontally, a follower lever controlled in its movement by the movement of said line delivery slide lever, a record reader responsive to the code characters in a control form for selectively actuating said release reeds, a linkage supervised by said follower lever for controlling the operation of said record reader and means also actuated by said follower lever successively to shift said release reeds to alternate matrix release escapements.

4. The combination set forth in claim 3, in which said linkage includes a floating lever responsive to the condition of said follower lever and to a signal received through said record reader for controlling the operation of said record reader.

5. The combination set forth in claim 3 including a spring for urging said follower lever into engagement with said line delivery slide lever, and a spring for urging the engagement of said shifting means with said follower lever.
